(57) **CLAIM**

The ornamental design for a computer display screen with graphical user interface for component proportionality, as shown and described.

DESCRIPTION

FIG. 1 is a front view of a first image in a sequence for a computer display screen with a graphical user interface for component proportionality; and,

FIG. 2 is a second image of a computer display screen with a graphical user interface for component proportionality. The rectangular broken line illustrates a computer display screen. The remaining broken lines illustrate portions of the graphical user interface. None of the broken lines form part of the claimed design.

The hatched shading in the figures indicates a contrast in appearance.

The appearance of the transitional image sequentially transitions between the images shown in FIGS. 1 and 2. The process or period in which one image transitions to another image forms no part of the claimed design.

1 Claim, 1 Drawing Sheet
